ELECTRIC LAMP

Vernon H. Kammer, East Detroit, Mich.

Application August 15, 1950, Serial No. 11,769

Term of patent 14 years

(Cl. D48—20)

To all whom it may concern:

Be it known that I, Vernon H. Kammer, a citizen of the United States, residing at 16152 Evergreen Street, in the city of East Detroit, county of Macomb, and State of Michigan, have invented a new, original, and ornamental Design for an Electric Lamp, of which the following is a specification, reference being had to the accompanying drawing, forming part hereof.

Figure 1 is a side elevational view of a lamp showing my new design;

Figure 2 is a top plan view thereof; and

Figure 3 is an end elevational view, taken from the left of Figure 1.

The characteristic features of my design are shown in full lines in the aforesaid drawing.

I claim:

The ornamental design for an electric lamp, as shown and described.

VERNON H. KAMMER.
